UNITED STATES PATENT OFFICE.

ROY WILLIAM YOUNG, OF GALLUP, NEW MEXICO, ASSIGNOR OF ONE-HALF TO GORDON B. SMITH, OF GALLUP, NEW MEXICO.

LUBRICATOR-FILLER.

1,260,117.

Specification of Letters Patent. Patented Mar. 19, 1918.

Application filed May 15, 1917. Serial No. 168,724.

To all whom it may concern:

Be it known that I, Roy W. Young, a citizen of the United States, residing at Gallup, in the county of McKinley and State 5 of New Mexico, have invented new and useful Improvements in Lubricator-Fillers, of which the following is a specification.

This invention relates to lubricator fillers and comprehends especially the provision of 10 means for forcing oil from a reservoir or oil bowl into the oil bowl of a lubricator.

Another object of the invention resides in the provision of a lubricator filler comprising an oil bowl through which is connected 15 a compressed air pipe for forcing oil therefrom through a discharge pipe leading to the bowl of the lubricator and having a drain pipe which may be used as an oil or water drain.

20 The invention also aims to provide a quick, satisfactory and efficient means for filling the oil bowls of locomotive lubricators to supplant the old hand method of filling and thereby extract a great saving of time.

25 With these and other objects in view, as will become more apparent as the description proceeds, the invention consists in certain novel features of construction, combination and arrangement of parts, as will be herein- 30 after fully described, illustrated and claimed.

In the drawings,

Figure 1 is a side elevation showing my lubricator filling means operatively connected to an engine lubricator and to the brake 35 valve of the locomotive air system.

Fig. 2 is a vertical sectional view through the oil bowl of the filler and its immediately associated parts.

Fig. 3 is a horizontal sectional view looking down against the top of the oil bowl of the filler, and

Fig. 4 is a detail view, partly in section of one of the valves.

Referring in detail to the drawings by 45 numerals, 1 designates as an entirety, an engine lubricator, known commercially as "The Chicago locomotive lubricator Class 'C'", and it is shown simply to illustrate the application of the filling means, it being understood that the invention may be applied to any kind of lubricator. The lubricator shown includes an oil bowl 1, condenser 2, circulating pipes 3, water valve 4, oil bowl drain nipple 5, and filling opening 6. It is 50 thought that the enumeration of the above 55

features will suffice to a sufficient understanding of the construction of the lubricator to make clear the function of my filling means when applied thereto.

The filling means includes an oil bowl 7, 60 here shown as having a hollow cylindrical body threaded externally to receive the top and bottom closing caps 8 and 9. A filling funnel or boss 10 is secured in the cap 8 and closed normally by the plug 11. A plug 65 valve 12 is connected to the nipple 13 protruding from the body of the oil bowl 7 adjacent the base plug 9 and to the casing of the valve is connected by a union 14, a feed or distributing pipe 15 which is connected 70 to a valve 16 having a casing 17 with a threaded nipple which screws into the opening 6 in the lubricator.

A compressed air pipe 17' is connected through a valve 18 to the body of a brake 75 valve 19 and is connected at its other end by a union 20 to an elbow pipe 21 making communication with the oil bowl 7 through the top cap thereof.

A drain pipe 22 is connected through the 80 medium of the valve 23 and coupling 24 to the drain nipple 5 of the engine lubricator. The other end of the drain pipe is secured by a coupling nut or union 25 to a T 26. The stem of the T is connected by a coupling 85 27 to a valve 28 mounted on a nipple 29 communicating with the oil bowl 7 through the cap 8 thereof. A valve 30 is connected by an elbow 31 to one end of the T head as shown. 90

In operation, oil from the bowl 7 is transferred to the bowl 1 of the locomotive lubricator through the feed pipe 15. The flow is caused by opening the valve 18 to admit air pressure to the air pipe 17, then opening 95 the discharge valve 12 and then the intake valve 16. When the lubricator has been filled or the desired quantity of oil transferred thereto it is preferable to stop the operation of the feeder by closing first the 100 valve 16, then the valve 12 and finally the valve 18. To drain a lubricator to the atmosphere, open the valves 23 and 30, but if it is desired to drain the oil back into the bowl 7, the valve 30 may be closed and the 105 valve 28 opened.

From the foregoing description taken in connection with the accompanying drawings it will be evident that I have provided a very simple and practical means for quickly 110

supplying a locomotive lubricator with oil from a reservoir.

While I have shown and described the preferred embodiment of my invention, it will be clearly understood that I do not wish to be limited to this construction, but may make such changes as will fall within the scope and spirit of the invention as claimed.

What I claim is:—

10 The combination with a locomotive lubricator, a closed oil bowl, a connection between the top of said bowl and the air pressure sys-

tem of the locomotive, a valve in said connection, a pipe connecting the top of said bowl and the drain outlet of the lubricator, 15 a valve adjacent each end of said pipe, a drain pipe connected to said pipe adjacent its lower end, a valve in said drain pipe, a pipe leading from the lower end of the bowl to the lubricator, and a valve adjacent each 20 end of said pipe.

In testimony whereof I affix my signature.

ROY WILLIAM YOUNG.
